UNITED STATES PATENT OFFICE.

THOMAS J. DIXON, OF MADISON, WISCONSIN.

MULTIPLE EXPANDER.

1,379,087.

Specification of Letters Patent. Patented May 24, 1921.

Application filed May 22, 1920. Serial No. 383,338.

To all whom it may concern:

Be it known that I, THOMAS J. DIXON, a citizen of the United States, residing at Madison, in the county of Dane and State 5 of Wisconsin, have invented certain new and useful Improvements in Multiple Expanders, of which the following is a specification.

My invention has for its object to provide a tube expander that is of a simple and 10 inexpensive construction and is so arranged and designed that the tool may be used to expand a wide range of sizes of tubes.

In its general nature, the invention comprises a shell composed of stepped portions 15 to fit the different sizes of tubes, the shell being bored to receive the mandrel and having pockets to receive expanding rollers which are adapted to be forced radially by the insertion of the mandrel, there being 20 provision for retaining the rollers against detachment from the shell by radial movement, the corresponding pockets of the several steps of the shell being in alinement with each other but slightly inclined with 25 relation to the axis of the shell.

In its detailed nature, the invention includes a novel structure by which the parts can be conveniently assembled.

The invention also resides in those novel 30 details of construction, combination and arrangement of parts, all of which will be first fully described, then be specifically pointed out in the appended claims, reference being had to the accompanying drawings, in 35 which:

Figure 1 is a perspective view of the shell and roller constituting a part of the invention.

Fig. 2 is a vertical longitudinal section 40 of the same, the mandrel being in place.

Fig. 3 is a detailed vertical section of the retaining collar.

Fig. 4 is a front elevation of the collar.

Fig. 5 is a cross section on the line 5—5 45 of Fig. 2.

Fig. 6 is a cross section on the line 6—6 on Fig. 2.

Fig. 7 is a cross section on the line 7—7 on Fig. 2.

Fig. 8 is a cross section, similar to Fig. 5, 50 of a modified form of the invention.

Fig. 9 is a detail section on the line 9—9 of Fig. 8, the roller being shown in dotted lines.

Fig. 10 is a detailed perspective view of 55 one of the retaining clips.

In the drawings in which like numerals of reference indicate like parts in all the figures, 1 represents the shell which is formed with a series of steps 2, 3, 4, etc., and which 60 is centrally bored, as at 5, to receive the mandrel 6. The largest step 4 of the shell terminates in a flared or expanded end 7 on which the collar 8 is forced by retaining friction and by a key 9. 65

Each section or step of the shell 1 has a radial pocket 10. The corresponding pockets of the several steps 2, 3 and 4 are in alinement with one another, as shown, but the axis of each group of rollers is 70 slightly inclined with regard to the axis of the shell, so that the tool will be self-advancing.

11, 12 and 13 designate the rollers which fit the pockets 10 of the respective steps 2, 75 3 and 4 of the shell. The pockets 10 of the steps 2 and 3 of the shell are provided with outer lips 14 which constrict the outside opening to prevent radial discharge of the rollers from the pockets and the inner 80 extremities of the pockets are constricted, as at 15, to limit the inward movement of the rollers toward the axis of the shell.

The walls of the pockets 10 of the step 4, however, are straight, as indicated in Fig. 5, 85 so that the rollers may be introduced through the pocket 10 of the largest step 14, the outward movement of the rollers 13 being limited by the recesses 16 in the collar 8. 90

In the modified form shown in Figs. 8, 9 and 10, the collar 17, corresponding to the collar 8 of the preceding form, is made integral with the shell and the wall of each pocket 10 is provided with a retaining lip 95 14. In this form, the rollers are all inserted through apertures 18 in the rear end of the shell and the rollers are held in place by clips 19 which fit over the collar 17 and have a portion 20 to extend down in back 100 of the rear roller 13 and have another portion 21 to clip into the recess 22 in the collar 17, the clips 19 being thus self-holding.

In operation, the tool is fitted into the 105 tube to be expanded, the tube fitting either the step 2, 3 or 4 as the case may be, depending upon the diameter of the tube. The mandrel 6 is then inserted in the usual manner to expand the rollers and thus cause 110 the expansion of the tube.

From the foregoing description taken in

connection with the accompanying drawings, it is thought that the complete construction, operation and advantages of the invention will be clear to those skilled in 5 the art.

What I claim is:

1. A tube expander comprising a shell having an axial bore, said shell being formed of a plurality of diameters to provide "steps," each of said steps having a radial roller receiving pocket, the inner portion of which pocket registers with the bore of the shell, rollers in said pockets, the pockets of the steps of lesser diameter having lips at their outer edges to restrain the rollers, the rollers in the respective pockets alining with each other, whereby the smaller diameter rollers may be inserted via the largest roller pocket into their respective 15 smaller pockets, means for retaining the largest roller in place, and a mandrel for forcing the rollers radially.
2. A tube expander comprising a tubular shell having plurality of portions of different diameters to form "steps," said shell having roller receiving pockets for each "step," rollers in said pockets progressively increasing in diameter from the smaller end to the larger end of the shell, the roller receiving pockets of the respective steps being arranged in sets, the pockets of corresponding position in the several steps of the shell being in endwise register and merging one with the other, whereby all of the rollers of 30 a set may be inserted through the largest pocket and distributed successively through the registering pockets beginning with that of largest diameter to their respective pockets and means for retaining the rollers 35 in place, when assembled, and a mandrel for forcing the rollers radially apart.

3. A tube expander comprising a shell

having an axial bore, said shell being formed with a plurality of diameters to provide "steps," each of said "steps" having 45 radial roller receiving pockets, the inner portions of which register with the bore of the shell, the pockets of the steps of lesser diameter having lips at their outer edges to restrain the rollers, sets of rollers of different diameters, one set for each stepped pocket, the respective sets of rollers alining with each other, whereby the smaller diameter rollers may be inserted via the largest roller pocket into their respective smaller 55 pockets, a collar on the shell with provision for retaining the rollers of largest diameter in place, and a mandrel for forcing the rollers radially.

4. A tube expander comprising a shell 60 having an axial bore, said shell being formed with a plurality of diameters to provide "steps," each of said "steps" having radial roller receiving pockets, the inner portions of which register with the bore of 65 the shell, the pockets of the steps of lesser diameter having lips at their outer edges to restrain the rollers, sets of rollers of different diameters, one set for each stepped pocket, the respective sets of rollers alining 70 with each other, whereby the smaller diameter rollers may be inserted via the largest roller pocket into their respective smaller pockets, a collar on the shell with provision for retaining the rollers of largest diameter 75 in place, said collar being separately formed from said shell, said collar and said shell being fitted together with a tight fit, a key for keying said collar and shell together, said collar having roller receiving recesses 80 into which the rollers may be expanded, and a mandrel for forcing the rollers radially.

THOMAS J. DIXON.
